UNITED STATES PATENT OFFICE.

VALENTINE G. BARNEY, OF CHARLES CITY, IOWA, AND R. LESTER BARNEY,
OF SWANTON, VERMONT.

STONE-SAWING MACHINE.

SPECIFICATION forming part of Letters Patent No. 377,595, dated February 7, 1883.

Application filed November 4, 1886. Serial No. 218,001. (No model.)

To all whom it may concern:

Be it known that we, VALENTINE G. BARNEY and R. LESTER BARNEY, citizens of the United States, and residents, respectively, of Charles City, Iowa, and of Swanton, State of Vermont, have invented certain new and useful Improvements in Stone-Sawing Machines; and we do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of our invention in perspective view. Fig. 2 is a longitudinal vertical section of the pump. Fig. 3 is a perspective view of the same. Figs. 4 and 5 are detail views.

Our invention relates to stone-sawing machines; and it consists in the construction and novel combination of parts, as hereinafter described, and pointed out in the claims.

Referring by letter to the accompanying drawings, A designates a drum, around which a coil of pipe is wound, p' p p p p designating the coils, one-half of the first coil, p', commencing at its mouth, being enlarged.

g designates an extension of the end coil, p', which extension connects with the discharge-pipe n. The drum and coiled pipe form the pump. This pump is a rotary pump and has its shaft journaled in bearings on the tank Q, which receives the mixture to be raised and deposited on the stone to be sawed.

It should be stated here that the tank Q should be always immersed in the mixture.

A' is a blade which is set on the outside of the pump at an angle to scrape the sand or other material used in sawing which may settle under the wheel to or near the mouth of the pump.

B designates a stuffing-box, on the inside of which is a circular groove, m, which is supplied with clear water under pressure from the pipe H, the pressure of the water in said groove in the pipe H to be greater than the pressure of the material being raised, so that the abrading material can never reach the packing around the pipe n. This groove is

not a positive necessity, however, as the water under pressure will be effective in preventing the material from reaching the packing without the use of the groove. It is better to use it, and we prefer to use it, and sometimes do so. The current of clear water, passing inwardly around and between the discharge-pipe n and the stuffing-box B, renders it impossible for the grit to reach the packing.

B' designates the pipe leading from the pump to the sand-cleaner. When the sand-cleaner is not used, the pipe B' would continue to the distributor E. When used, it is a receiver into which the mixture is forced for the purpose of cleansing the sand. The sand being forced in an upward direction, the worn particles rise and pass off or out through the pipe C', the pipe G supplying a stream of clear water to assist in cleaning the mixture. When the cleaner is not used, the mixture goes directly to the distributor.

H' is a pipe leading from the cleaner C to the distributor E, two sections of said pipe being connected at D by flexible hose. The pipe H' is supported near its elbow by a cord, f, running over a pulley and connected at its lower end to the frame of the sawing-machine.

D' is a loose-fitting pipe which is secured to the lower end for the purpose of raising or lowering the distributor E of the pipe H' by set-screws d, so as to raise and lower it on the pipe H', said pipe D' leading to the distributor E. The distributor E consists of a hollow stem, X, provided with two downwardly-inclined hollow wings. The distributor is provided with a wedge-shaped divider, Z, which may be turned to conduct the material to either wing or to both wings V' W, as may be desirable or necessary. The form of the distributor, however, is not essential, and any other form may be used, if preferred.

M designates the saw-frame, which is moved back and forth by power over the stone to be sawed.

N is the slanting bottom which receives and conveys the mixture after passing the saws back into the tank Q, causing said mixture to pass through the wirescreen O and the spout P.

S is a box which receives the worn material which overflows from the receiver C through

the pipe C', and this box S is provided with a partition, s. On one side of this partition the box S is connected by a vertical pipe, V, leading to the tank Q. On the other side of the 5 partition the box is connected with a spout, U, which carries off the worn sand or other material away from the machine.

X' is a float in the tank Q, which rests on the water therein. A cord, 1, is attached to the 10 float X', said cord 1 passing over a pulley, 2, and is connected with a flexible pipe, T, having a discharge-pipe, t. A weight, W', is connected to the opposite side of the pipe or hose T by a cord, 3, passing over a pulley, 4.

15 K is a sand-feed box having a descending slanting or inclined bottom. The sand-feed box communicates through a spout, L, with the spout P, leading to the tank Q.

Z' Z' are cross-bars, which are suspended by 20 chains, screws, or otherwise, and held in position by slides b b b b, which slides move up and down on rods a a a.

The saw-frame M is suspended by rods q q q q, connected to said cross-bars Z' Z'. Said saw-frame is prevented from swinging laterally by the crossed braces Y Y, and can move longitudinally only. The rods q are suspended on the bars Z' by the loops c, and have at their lower ends the loops c', in which rest the bearing-pieces c' of the saw-frame M. But one saw-frame is represented in the illustration, as that is sufficient to show our invention; but we can and do use a number of gangs, which will be usually done, and they will all be supplied with 35 abrading material by one pump, the pipes leading to the different gangs, the latter being connected to the receiver C. When the supply of material is greater than necessary, the float X' will rise and the cords and weight W' will 40 carry the discharge-pipe t to the outer side of the partition s, so that it will pass out of the machine. When the material is scant, the float falling will draw the pipe t to the inner side of said partition and the material will pass down 45 the pipe V to the tank Q.

The operation of the machine is as follows: Tank Q being supplied with the sawing or abrading material, the machine is set in motion. The pump at each revolution takes in 50 sand and water, or other abrading material used for sawing, and air, the proportion being about three parts air to two parts of the mixture used for sawing. As the revolutions continue and the mixture ascends the discharge-pipe, the pressure from the column of the mixture in the discharge-pipe forces that in the coils to rise to one side. All these columns of the mixture in the coils combined, and being separated by the air-columns, which are 55 compressed considerably, force the mixture to a height in proportion to the number of coils. The mixture passes into the receiver C and is there cleansed, as described heretofore, the cleansed material passing through pipe H' to 60 the distributer, where it is distributed to the saws, whence it falls onto the slanting bottom N and passes through screen O and spout P

back to tank Q. The waste and worn particles that pass off through C are replaced by fresh sand and water from the feed-box K, the 70 material being washed down by a jet-pipe, J, from the elevated water-tank F through spout L and through screen O and spout P. The mixture in passing through screen O is separated from gravel and other objectionable material which it is desired to take out. The 75 tank F supplies the water to the jet-pipe J.

A' is a shaft journaled in bearings secured to the main frame operated by a crank-handle, A², and provided with a ratchet-wheel, A³, 80 which is controlled by the pawl A⁴, attached to the main frame.

A⁵ A⁶ are ropes or cords secured to the bars Z', passing over the pulley A⁶ and winding on the shaft A', those on opposite sides thereof 85 winding in opposite directions. By this means the saw-frame can be raised or lowered at will.

When the cleaner is not used, the abrading mixture goes directly to the distributer. 90

The material may go the round many times before being used up and worn out. The distributer is adjustable as to height for high or low blocks by means of cord f.

The pump herein described can be used for 95 raising sand or other abrading material for the purpose of scouring or finishing marble on a rubbing bed or wheel, such as is commonly used in mills for such purposes, or it may be used for any other machine where sand must 100 be raised for finishing marble.

I' is a cord having a hand-hold at its lower end for the purpose of turning the valve f' and regulating the flow of material to the distributer. 105

We are aware that a pump working on a principle somewhat similar to ours, although of different construction, is now in use. Our construction, however, is an improvement on the other, that being made by a hollow passage which leads from the outside to the center, the pipe being coiled around and around upon itself. Our construction is better than that for the reason that it is more easily made, the coils being on larger curves and aligned 110 horizontally upon the supporting-drum A. In the old construction the wheel has to be made too large in order to get coils enough to raise the material to the height that may be desirable, while ours can be extended to any length 120 without increasing the diameter of the wheel, and the abrading material will be raised to a height proportional to the length of the coils. 115

The method is preferable to all others for the reason that there are no valves to wear or clog. 125 The mixture is discharged in a continuous stream without friction or wear, except at the stuffing-box, and that we protect as described. It has also the advantage of running at a slow speed, only about twenty revolutions per minute being required. 130

In the application of Valentine G. Barney, filed June 3, 1887, Serial No. 204,060, a machine in many respects similar to that shown

in present application is shown; but it has the additional features of the step lubricated by water and the divided pipe to separate the worn from the sharp sand. Neither of these is claimed in present application. In Valentine G. Barney's application the vertical sand-cleaner, the stuffing-box with packing to protect the piping joint, the coil-pump, and the mechanism to raise and lower the saw-frame are not shown. Both being stone-sawing machines in which sand and water are fed to the saws, they must necessarily have some points in common; but the points of difference have been carefully noted and stated.

Having described this invention, what we claim, and desire to secure by Letters Patent, is—

1. In a stone-sawing machine, the combination, with a reciprocating saw-frame, a distributor, and the vertical sand-cleaner C, situated between the pump and distributor, of the coil-pump composed of the coils *p* and the receiving-coil *p'*, of larger diameter than the former, which coils are wound on a horizontal drum, the piping connecting said pump with the cleaner, and the piping connecting the cleaner with the distributor, substantially as specified.

2. The combination, in a stone-sawing machine, of a pump secured to a revolving pipe, *n*, the stationary pipe B, the stuffing-box hav-

ing the packing *t*, and the clear-water pipe H, connecting with the stuffing-box B, substantially as specified.

3. In a stone-sawing machine, the combination of the coil-pump consisting of coils wound on a horizontal drum, the tank Q, the cleaner C, the piping connecting said pump and cleaner, the discharge-pipe C' from the cleaner, the distributor, the piping connecting the distributor and cleaner, and the flexible joint in said piping, substantially as specified. 35

4. The combination, with the tank Q, the pump, the receiver, and the pipe connecting the pump and receiver, the pipe C', flexible pipe T, the weight W', its cord, and the cord 45 connecting the flexible pipe T to a float in the tank Q, the tank S, and spout U, substantially as specified.

5. The combination, with the coil-pump consisting of coils wound on a horizontal drum, 50 of the tank Q and the curved and inclined director blade or plate A', substantially as specified.

In testimony whereof we affix our signatures in presence of two witnesses.

VALENTINE G. BARNEY.
R. LESTER BARNEY.
